CLAIM

The ornamental design for a combined bottle and cap,
as shown and described.

DESCRIPTION

FIG. 1 is a top perspective view of a combined bottle
and cap showing my new design;

FIG. 2 is a side elevational view thereof, the opposite
side is the same;

FIG. 3 is a top plan view thereof; and

FIG. 4 is a bottom plan view thereof.

The figures in the drawings are shown on different
scales.

FIG. 1

FIG. 3

FIG. 4

FIG. 2
